UNITED STATES PATENT OFFICE.

EDWARD J. BRANDT, OF WATERTOWN, WISCONSIN.

PACKAGED-COIN HOLDER.

1,358,411.

Specification of Letters Patent.

Patented Nov. 9, 1920.

Application filed February 4, 1918. Serial No. 215,317.

To all whom it may concern:

Be it known that I, EDWARD J. BRANDT, a citizen of the United States, residing at Watertown, in the county of Jefferson and State of Wisconsin, have invented certain new and useful Improvements in Packaged-Coin Holders, of which the following is a specification, reference being had therein to the accompanying drawing.

This invention relates to packaged coin holders and is designed more particularly as a convenient adjunct for the desks of cashiers, tellers and others wherein it is desirable to have at hand packages of coin for change making. The invention is particularly desirable for use in connection with the "Brandt automatic cashier."

The object of the invention is the provision of a holder for packaged coin which will permit of the handling of a number of packages of coin and to associate therewith a fixture whereby the coins may be readily removed from the holder as needed.

A further object is the provision of a coin holder for coin wherein the coin may be easily and readily transported to the vault or safe when not needed and from there to the cashier's desk and is so fashioned that the holder can be readily placed in stable position to permit the removal of a package of coin with but little trouble and with great convenience.

In the accompanying drawings there is shown a form of holder and its associated rack or cabinet but it is to be understood that the same is herein depicted for the purposes of clearly setting forth the inventive idea without necessarily limiting the invention to the particular construction shown, and it is to be borne in mind that changes and modifications may be made without in the least departing from the nature and spirit of the invention.

Figure 1 represents a front view in elevation, the upper part being broken away, of a receiver or rack with the holders and coin in position.

Fig. 2 is a section through the line II—II of Fig. 1.

Fig. 3 is an elevation of the holder.

Fig. 4 is a plan of a blank from which the holder is constructed.

Fig. 5 is a section through the line V—V of Fig. 3, and

Fig. 6 is a perspective view of the receiver support.

The packaged holder is formed conveniently of a single piece of metal having a supporting bottom or body part A and upstanding sides B, these sides are formed with a series of oblong openings through which the printed designation on the sides of the coin packages C are visible. The vertical width of sides B is substantially that of the length of the coin packages C so that the top of the packages will be practically flush with the edges of the holder. In construction, the parts A and B are of a single blank with the sides bent up constituting substantially a U-shaped receiving member of convenient length to receive a number of packages of coin as indicated in the drawings. At the opposite ends of the bottom A of the blank there are extensions D of a width slightly less than the bottom A, but of a length sufficient to support thereon a package of coin as shown in Fig. 3. The extreme outer portions of these extensions D are cut away as at d' for purposes presently to be described. As shown in Fig. 3 the receiving extensions D are bent down slightly below the plane of the bottom of the holder.

E, E designates U-shaped bail members pivotally supported in the sides B adjacent the bottom and of a length sufficient to extend well over the supporting extensions D. These bail members are designed and intended to be slightly elevated to a position wherein the connecting bar portion of the bail will embrace approximately the center of the coin package C thereby holding the package in alinement with the succeeding coin packages. Both ends of the holder are provided with bails E and as a means for retaining the bails in their elevated position as well as in their depressed position, there are formed elongated outwardly pressed knob portions e over which the side parts of the bails are sprung, these pressed out portions being adjacent the bottom of the sides of the holder near the end as shown in Fig. 5. Immediately above the knobs e is a small stop point e' pressed out from the blank and serving as a limiting stop for the upward movement of the bail. In practice the bail E is sprung over the knob e and is allowed to rest between the

parts e and e' in the position as shown in Fig. 5, but owing to the flexibility of the sides of the bail, when it is desired to release the package which is at the end, it is only necessary to press the end of the bail downward or toward the extension D the same springing over the knob e and engaging below the lower end thereof. In this position the end of the bail will lie in a position as shown in Fig. 3 at the right with its extreme end resting on the projections D , and held by the lower end of the knob e . The construction thus described is very simple and can be made with but little expense and represents substantially a U-shaped elongated coin holder into which packages of coin can be readily placed and which is capable of holding not only the coin packages between the upstanding sides B but also a package at each end on the extension D . In this condition when loaded a series of holders can be placed one on top of the other in the vault or safe and in that particular represents a convenient coin holding tray which can be taken in any convenient number from the storage vault to the cashier's desk for use.

The pronounced advantages of the holder as above described is its adaptability for use in the dispensing of the coin packages as the cashier desires. With that in view a suitable receiver or cabinet is formed comprising a base F with upstanding sides F' of any convenient height. By preference the height should be that of the length of the holders although that is not entirely necessary. The receiver is provided at a point above the bottom sufficient only for the operator to place his hand into the receiver, with a series of supporting ledges G , the same conveniently being arranged one back of the other as shown in Fig. 2. These ledges are provided with curved seats g and cut-out portions g' which extend laterally as at g^2 terminating at a point closely adjacent to a line in the plane of the bottom of the holder when the latter is in position as shown particularly in Fig. 1.

Adjacent the extended cut-out portion g' are grooves g^3 , g^4 oppositely arranged and spaced to receive the extreme projecting ends of the projections D of the holder, the cut-out portions d' of the latter resting on the top of the part G . It will be noticed that the supporting parts G are relatively narrow, as shown particularly in Fig. 2, and form holders or saddles the upper surface of which is curved to conform to the curvature of the coin package. The latter however project well beyond the edges of the supporting surface G . In the cabinet or receiver there may be any number of these supporting surfaces employed but for convenience three are shown in Fig. 3, they are spaced

well apart above the hand space. The operator by using his fingers can easily move the coin packages transversely from the curved seats g from which they will fall into the hand of the operator as they leave the seats.

In operation the holder is filled with coin packages stored therein. It is then taken, when to be used, and with the lower-most coin package held in position by the bail E , the holder is uprighted and is placed in the receiver with the lower exposed package C resting on the seat G . The bail in this instance enters the cut-out portion g^2 while the extended bifurcated end of the part D is fitted into and along the grooved part of the support G , the prongs d' of the holder entering the grooves g^3 , g^4 . This stabilizes the holder and when it is desired to remove the lower package the bail is easily sprung over the knob e and swung toward the right until it engages the end of the extended groove or cut-out portion g^2 . In this position the lower package is free for removal, it requiring but a slight canting movement in the first instance. The position of the bail near the bottom of the holder enables the former to be swung out of the path of the descending or succeeding packages of coin so that the latter as they follow down upon the removal of the first package can be promptly moved from the surface g and allowed to drop into the hand of the operator. It may be found convenient to place a series of wires or rods H transversely across the receiver between the respective holders for the purpose only of preventing lateral tip of the holders after being positioned in the receiver. Should the operator desire to remove two or three packages of coin at one time it would be necessary only for him to engage with his fingers the last package, move it forward until it engages the next preceding package and so on tip a plurality of packages from the seats into his hand. Of course the receiver can be made and probably will be constructed to receive a greater number of holders and holders of different sizes for the different packaged denominations. Conveniently the inclined upper wall of the extension g^2 is employed as a means against which the lower end of the bail engages and assistance is thereby afforded to stabilize the holder in its adjusted position preventing any tendency of the holder moving in the direction of discharge as the coin packages are removed by the operator. Conveniently the different compartments of the receiver above the removal compartment may be divided by partitions as at F^2 . The offsetting of the extensions D of the package holders as shown in Fig. 3 is for the purposes of permitting the bail to be moved beyond the plane of the end of the succeeding coin packages so that

the succeeding coin packages can be removed from the holders when positioned in the receiver without the bail interfering.

As stated many changes can be made and 5 obviously if desired the holder can be formed with a top but it is more convenient to have an open U-shaped form of holder.

With reference to Fig. 1 of the drawings, it will be seen that the bail E is illustrated in 10 two different positions. When the bail is in position at the end of the slot g², as illustrated in full lines at the left side of said Fig. 1 of the drawings, the bail prevents the removal of a coin holder. This prevents accidental dropping of the packages which 15 would result if the coin holder were removable. If the bail is in the position indicated in full lines at the right of Fig. 1 where the loop of the bail is in registration with the 20 part g', the coin holder may be removed, and by reason of the position of the bail at this time, this will prevent the dropping of a coin package out of the end of the holder.

Having thus described the invention what 25 I claim and desire to secure by Letters Patent is:—

1. A packaged coin holder comprising a receiving member having a coin support therein with a space therebelow for the insertion of the hand of the operator, a coin holder positioned above and resting on the support the said holder having side parts and an open end portion for the purpose described, said support having an engaging 30 part, and a movable member on the coin holder adapted in one of its positions to engage over said open end portion to retain the coins and adapted in another position to contact with the engaging part of the support whereby to release the coins.

2. In a coin dispenser, the combination of a support, a coin holder comprising a substantially U-shaped member adapted to support a plurality of packages of coin with 45 the side arms of the U-shaped member overlying the sides of the packages, the U-shaped member being open at its lower end, and a supporting part depending from the base part of the U-shaped member adapted 50 to rest upon the support and space the sides of the U-shaped member at the lower open end thereof above the support a sufficient distance to permit the sidewise movement of a package of coins from the holder, and reusable means on the holder coöoperating 55 with the support to prevent withdrawal of the coin packages.

3. A coin holder comprising a receptacle adapted to support a plurality of packages 60 of coins arranged in superimposed relation side upon side, said receptacle having a lower open end, a projection at the edge of the lower open end adapted to position the lower end above a package receiving 65 port, and a swinging arm mounted on the

receptacle to retain the lowermost package, and adapted to be moved into a position to permit the removal of the package laterally between the lower end of the receptacle and package receiving support.

70

4. In a coin holder, the combination with a receiver having a package supporting member fixed therein of a width less than the width of the diameter of the coin package and means for supporting a series of 75 packages of coin arranged side to side above the support, the lowermost package being adapted to rest upon the support and the package supporting member having an open side spaced from said supporting 80 means a sufficient distance to permit sidewise removal of the lowermost package at will.

5. In a coin holder, the combination with a support having a series of packages of 85 coin, a holder for the coins, means for supporting the holder on the said support and a movable member carried by the holder adapted to be moved from a position to prevent the removal of a package of coins to a 90 position to permit the removal thereof.

6. In a coin holder, the combination with a receiver, of a series of supports for coin packages spaced apart and coin holders having open ends arranged on the supports 95 with their open ends in alinement with the supports and movable means for preventing the removal of a package from the supports when the holders are in position.

7. In a coin receiver and dispenser, the 100 combination with a receiver and a coin carrying element, of a pivoted bail on the said element arranged to be swung across the end of the element and means on the holder for engaging the bail for stabilizing the holder 105 on the support.

8. In a coin dispensing device, a receiver having a support therein, a holder for receiving a series of packages of coin, an extension on the holder of a length to permit 110 a package of coins to be moved from the holder sidewise and from the support and means for retaining the lower-most package in position beyond the side of the coin holder, said means comprising a swinging 115 element substantially as described.

9. A coin holder comprising a U-shaped body portion into which packages of coins can be placed and extended end portions with removable means for embracing a package of coins when positioned on the end portions.

10. A coin holder comprising a blank having a bottom part and upstanding side portions with outwardly extending end portions 120 arranged below the plane of the bottom part and pivoted bails extending over said extensions.

11. A coin holder comprising a body for receiving a series of packages of coins and 130

an end extending part, of means for retaining a package of coins on said end part comprising a swinging bail secured to the holder and overlying said end extension.

5 12. In a coin holder, a body part shaped to receive a plurality of packages of coin and a bail member arranged to extend beyond the ends of the holder with means for holding the bail in different positions of adjustment.

10 13. A coin holder comprising a back and sides, the back having an extension at one end and said holder being open at said end, said holder being adapted to be supported upon said extension in upright position whereby to receive a plurality of packages of coins arranged side upon side, and means for retaining all of said packages in position in the holder comprising a bail pivoted to the sides of the holder and adapted to swing below the open end of the holder and engage the lowermost package.

15 14. A coin holder comprising a back part and sides adapted to receive a plurality of

packages of coin with one end of packages in contact with the back, said back having parts extending beyond the ends of the sides forming supporting means, and swinging bails pivoted to the sides, one at each end to overlie the ends of the holder, said holder being open at the ends, and retaining lugs on the sides of the holder for said bails.

20 15. A coin holder comprising a body part adapted to receive a plurality of packages of coins and having an open end, the base of the body part having an extension beyond the open end, and a swinging member arranged to be projected across said open end and cooperating with said extension for retaining the packages in place, and said extension being bifurcated.

In testimony whereof I hereunto affix my signature in the presence of two witnesses.

EDWARD J. BRANDT.
